DESIGN FOR A PUNCH BOARD OR SIMILAR ARTICLE

William B. Vandegrift, Dayton, Ohio

Application June 26, 1939, Serial No. 85,686

Term of patent 3½ years

To all whom it may concern:

Be it known that I, William B. Vandegrift, a citizen of the United States, residing at Dayton, county of Montgomery and State of Ohio, have invented a new, original, and ornamental Design for a Punch Board or Similar Article, of which the following is a specification, reference being had to the accompanying drawing forming part thereof.

board or similar article showing my new design.

I claim:

The ornamental design for a punch board or similar article, as shown.

WILLIAM B. VANDEGRIFT.
